UNITED STATES PATENT OFFICE

ERIC SLATER, OF HEATON, BOLTON, ENGLAND, ASSIGNOR TO GEORGE TAYLOR (BRASS FOUNDRIES) LIMITED, OF BOLTON, ENGLAND

MEANS FOR AUTOMATICALLY REMOVING WATER FROM BOATS

Application filed October 16, 1930, Serial No. 489,134, and in Great Britain December 16, 1929.

This invention has for its object to provide improved means for automatically removing water from the interior of fast motor boats while in motion.

The invention comprises an ejector which is situated at the underside of the boat and depends for its action on the motion of the boat through the water, and a regulating valve situated within the boat.

In the accompanying sheet of explanatory drawings:—

Figure 1 is a side elevation and Figure 2 a cross section of an ejector constructed in accordance with this invention.

In carrying the invention into effect as shown, we employ a shallow hollow member forming a channel *a* of rectangular or other cross section which is closed at one end (*b*) and open at the other (*c*), and is adapted to be attached to the underside of the boat *d*. This channel is preferably tapered at its forward closed end *b* to minimize resistance, and the open end *c* is at the rear. On the upper side of the channel and preferably near its closed end is arranged a tubular extension *e* which projects through the bottom into the interior of the boat, and within the extension is arranged a valve *f* which controls an aperture *g* opening into the interior of the channel. The extension is perforated as at *h* to allow water to pass into it from the bottom of the boat. The extension is also provided with a removable cap *i* which carries a screwed stem *j* whereby the valve can be actuated.

Due to the action of a boat moving swiftly, suction is set up within the channel *a*, and on opening the valve this effect can be utilized for withdrawing water automatically from the interior of the boat bottom.

To prevent automatically return flow of water when the boat is standing or moving slowly, we combine with the aperture *g* a non-return valve *k* which is held on its seating by a light spring *l*.

By this invention we are able to effect withdrawal of water from the boat while in motion in a very simple and convenient manner.

Having thus described my invention what I claim as new and desire to secure by Letters Patent is:—

In means for automatically removing water from boats, the combination comprising a hollow channel having an open end and adapted to be attached to the underside of the boat, a cylindrical hollow and perforated extension from the channel adapted to project into the boat, a pair of coaxial valve seatings within the extension, a hand operated valve co-operating with one of said seatings, a screwed stem associated with said valve, a 55 screwed cap on the said extension through which the stem passes and engages, a finger piece on the outer end of the stem, a non-return valve co-operating with the other seating, and a spring whereby the non-return 60 valve is held on its seating, substantially as described.

In testimony whereof I have signed my name to this specification.
